UNITED STATES PATENT OFFICE.

J. TALMAN BUDD, OF BUFFALO, NEW YORK.

SUSPENDERS.

SPECIFICATION forming part of Letters Patent No. 329,433, dated November 3, 1885.

Application filed April 6, 1885. Serial No. 161,298. (No model.)

To all whom it may concern:

Be it known that I, J. TALMAN BUDD, a citizen of the United States, residing at Buffalo, in the county of Erie and State of New York, have invented certain new and useful Improvements in Suspenders; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention consists in certain improvements in suspender attachments, as follows: first, in a device for suspenders, consisting of a metallic or other suitable plate attached to the suspender-ends, in combination with the drawers-supports connected to said plate by a cast-off, substantially as set forth; second, in a device for suspenders, consisting of a metallic or other suitable plate attached to the suspender-ends, in combination with the drawers-supports connected to said plate by a cast-off, and means, substantially as described, for adjusting the said drawers-supports in length or position, or both, substantially as set forth; third, in an improved construction by means of which the ends of the suspender-straps are made adjustable as to length; fourth, in certain details of construction of the various parts of my improved suspenders, which will be more fully hereinafter described and claimed.

In the drawings, Figure 1 is a perspective view of my improvements, showing the suspender-end detached from the suspender proper. Figs. 2 and 3 are modifications thereof. Fig. 4 is a rear view of the clasp shown in Fig. 1. Fig. 5 is a rear view of the clasp shown in Fig. 2. Fig. 6 is a rear view of the clasp shown in Fig. 3. Fig. 7 is a partial front view in perspective of the clasp or slide shown in Fig. 1, by means of which the suspender proper is adjusted as to length. Fig. 8 is a partial back view, and Fig. 9 is a partial front view, of modifications of the clasp or slide shown in Fig. 1. Fig. 10 is a cross-section of the fastener for securing the extreme end of the suspender proper shown in Fig. 1, and Fig. 11 is a partial perspective

rear view of the modification thereof shown in Fig. 2. Fig. 12 is a view of the pattern from which the clasp shown in Figs. 1 and 4 is formed. Fig. 13 is a view of the pattern from which the clasp shown in Figs. 2 and 5 is formed, and Fig. 14 is a view of the pattern from which the clasp shown in Figs. 3 and 6 is formed.

Referring to the drawings, I have shown in Fig. 1 the preferred form of the different parts constituting my improvements, in which the double detachable drawers-support consists of the hanger *a*, having within its frame the cross-bars *a' a'*, (see Fig. 4,) and at its top the T-shaped projection *a''*, by means of which the hanger is attached to the clasp above. To this hanger are adjustably attached the flexible straps *b b'*, having their respective ends passing over the bars *a' a'* of the hanger *a*, the end of strap *b* being secured to the clamp *c* upon the strap *b'*, and the end of strap *b'* secured to the slide *c'* upon the strap *b*, the loops thus formed, together with the slide and clamp, making the drawers-supports adjustable both as to position and length. At the lower ends of these straps *b b'*, I secure a suitable device for attaching the ends to the drawers, those shown in Fig. 1 being safety-pins *d*, having double spring ends, one shown closed and the other open.

e is the clasp in which the flexible pants-supporters *f f'* are secured. This clasp *e* is formed from the blank or pattern shown in Fig. 12, in which the frame of the clasp consists of the portions *e' e'*, upon which the wings *e'' e''* are turned, upon the dotted line *e''*. Below the portions *e' e'* are the extensions *e'' e''*, between which is the slot *e''*, and at either side are the wings *e'' e''*. At the outside of the portions *e' e'* are the wings *e'' e''*, and on the inside are the additional wings *e'' e''*. *e''* is a narrow strip with the side lugs, *e'' e''*. Between the wings *e'' e''* is the narrow strip *e''*, with side lugs, *e'' e''*. At the inner sides of the wings *e'' e''* are the auxiliary wings *e'' e''*.

The operation of forming the clasp *e*, as shown in Figs. 1 and 4, from the blank just described is as follows: The ends of the flexible pants-supports *f f'* are laid upon the portions *e' e'* and the wings *e'' e''* turned down over them. The extensions *e'' e''* are then turned over, their side wings, *e'' e''*, resting un-

derneath the wings $e^2 e^2$. The wings $e^6 e^6$ and $e^9 e^9$ are turned over, as shown in Fig. 4, and serve to securely inclose and hold the supporters $f f$ between the parts $e' e'$ and $e^2 e^2$.

Referring to Fig. 1, the strip e^8 is shortened by means of the bend e^{13} , and its side lugs, $e^9 e^9$, rest behind the points $e^{14} e^{14}$ of the parts $e' e'$. At or near the lugs $e^9 e^9$ of the strip e^8 a shoulder is formed by bending down such strip. The strip e^{10} , after being bent down, has its lower end resting behind the turned-up wings $e^3 e^3$ in the rear of the slot e^4 , the side lugs, $e^{11} e^{11}$, resting against the upper portion of the wings $e^3 e^3$. This strip e^{10} has the same bend as strip e^8 near its end to form a shoulder. The flexible pants-supports are made in the form of a loop, upon which slides a double loop, g , which forms a button-hole at the end, in which the button can be locked by pushing down the same under the edge of the button.

The manner in which the end of the suspender proper is adjusted as to length is as follows:

Referring to Figs. 1 and 7, h is the back of the frame of the clasp, formed with the side wings, $h' h'$, in the upper portions of which is pivoted the clamp h^2 , having the lever h^3 for operating such clamp. In the lower ends of the wings $h' h'$ is pivoted the roller h^4 , which is below and in line with the back h of the frame. The shoulder-strap k passes down between the back h and clamp h^2 of the clasp just described, in which it can be secured at any point. The portion h' below the clasp is turned up, forming the loop or bend h^2 , and is carried over the roller h^4 and down again to a point in the portion h' , and its end h^3 secured thereto.

By means of the construction just described the shoulder-strap can be lengthened or shortened, as desired, by moving and securing same in the clasp, it being observed that the amount of lengthening or shortening of the strap is equal to the distance through which the clasp has been raised or lowered upon the shoulder-strap.

l is a loop through which the bend h^2 of the strap passes. This loop has secured to its lower portion the T-shaped hanger l' , adapted to engage with the clasp e . To attach the shoulder-strap to the clasp e , the loop l and its hanger l' are placed at right angles to the clasp, and the hanger l' is passed into the slot at the top of the clasp against the spring action of the strip e^8 , and resting against the spring-strip e^8 beyond the shoulder and within the slot, such shoulder preventing accidental detachment. The drawers-supports are attached to the back and lower part of the clasp e in the same manner by inserting the hanger a^8 in the slot e^4 . (See Fig. 4.)

The means for removably attaching the end k^3 of the shoulder-strap to the portion h' is arranged as follows: m is the front portion of the frame, at the ends of which are the recessed wings $m' m'$, within which are pivoted

the cams m^2 . The end k^3 of the shoulder-strap is covered by the metallic clip m^3 , having the end shoulders, m^4 . The frame m is placed over the strap k' , and the clip m^3 is placed between the cams $m^2 m^2$ and strap k' , the shoulders resting within the wings. The cams m^2 are turned down upon the shoulders m^4 of the clip m^3 , holding it secured in the position shown.

In Fig. 2, n is a modification of the clasp e , and is formed from the blank shown in Fig. 13.

The strips $n' n^2$ in Fig. 13 form the spring-catches shown in Figs. 2 and 5. In cutting out these strips the slots $n^3 n^4$ are left, behind which the ends of the spring-catches $n' n^2$ rest.

The loop l (shown in Fig. 2) has the hanger on the rear side, and is engaged with the clasp n by passing it beyond the end of spring-catch n' into the slot n^3 . This adjustment applies equally well to both the front and back of the clasp n .

In Fig. 3 another modification is shown, in which the front spring-clasp, n' , is shown attached to the loop l , and the hanger l' forms a part of the frame of the back spring-clasp, n^2 . The spring-clasp n^2 and its frame for holding the flexible suspender-ends are formed from the blank shown in Fig. 14, and Fig. 6 shows a rear view of the finished clasp.

In Figs. 2 and 11 is shown a modified form of the device for securing the end k^3 of the shoulder-strap to the portion h' , in which the cams m^2 operate in a different direction.

In Fig. 2 is shown a modified form of clasp h (shown in Fig. 1) for adjusting the length of the shoulder-strap, and Fig. 8 shows a partial rear view. The clamp h^2 , with its engaging teeth, is rigid in the wings, and the roller h^4 is located in the rear thereof, and above the line of the teeth.

It will be seen from Fig. 2 that the downward pull of the shoulder-strap in passing over the roller produces a leverage, which causes the engagement of the teeth on the clamp with the shoulder-strap.

In Figs. 3 and 9 another modification is shown, in which the engaging teeth are on the top of the back frame, h , instead of the portion h^2 .

In applying this modification to the shoulder-strap the roll h^4 is in front, producing a leverage which throws the teeth upon the portion h in engagement with the rear side of the shoulder-strap k .

The style of clasps shown in Figs. 1, 2, and 3 of the drawings, connecting the pants and drawers-supports to the shoulder-strap, is reserved for subject-matter of another application filed by me May 20, 1885, the serial number of which is 166,117.

I claim—

1. A device for suspenders, consisting of a metallic or other suitable plate attached to the suspender-ends, in combination with the drawers-supports connected to said plate by a cast-off, substantially as set forth.

2. A device for suspenders, consisting of a

- metallic or other suitable plate attached to the suspender-ends, in combination with the drawers-supports connected to said plate by a cast-off, and means, substantially as described, 5 for adjusting the said drawers-supports in length or position, or both, substantially as set forth.
3. In suspenders, the combination, with the end of the shoulder-strap, of a combined clamp 10 and roller, constructed substantially as shown and described, by means of which such shoulder-strap is adjustable as to length, substantially as shown and described.
4. In suspenders, in combination with the shoulder-strap, the combined clamp and roller, 15 consisting of the frame h , having the wings h' , the clamp h^2 , with its lever h^3 , and the roller h^4 , substantially as shown and described.
5. In suspenders, and in combination with 20 a shoulder-strap, a double clasp having the
- two catches—one for attachment to the shoulder-strap and the other for the reception of the drawers-supports—substantially as shown and described.
6. In suspenders, and in combination with 25 a shoulder-strap, a clasp having two catches and a frame adapted to receive and hold the ends of the pants-supports, substantially as described, such clasp being adapted for attachment to the end of the shoulder-strap and 30 for the reception of the drawers-supports, substantially as shown and described.

In testimony whereof I have signed my name to this specification in the presence of two subscribing witnesses.

J. TALMAN BUDD.
